UNITED STATES PATENT OFFICE

2,003,744

OIL COOLER

James Flockhart, Newark, N. J.

Application January 31, 1935, Serial No. 4,391

1 Claim. (Cl. 257—241)

This invention relates to a novel oil cooler for engines which will be found particularly adaptable, because of its practical utility, to that field of structures embodying marine engines, or conversion motors applicable to aeroplanes, automobiles and similar conveyances.

In reducing the inventive conception to actual practice I find it expedient and practical to employ a one-piece bronze casting, such as is immune to rust and corrosion, leak-proof and otherwise thoroughly practical and up to date, whereby to provide an ingenious structure sufficiently inclusive in its features and special design to accomplish the purposes for which it is intended.

Desiring to remain within the range of simplicity required of a structure of this classification, I have provided an all-metal one-piece arrangement, which it is believed, transcends in advantages and importance similar prior art devices and is otherwise susceptible of fulfilling the needs and requirement of the trade, thereby insuring its unqualified endorsement as an unequalled achievement in this specific line of endeavor.

By way of critical observation it will be discerned by those skilled in the art that the improved structure is characterized by a consolidation of elements which will promote longevity and will function as exclusive and distinguishing features in conditioning the oil as it is circulated therethrough, whereby to permit the temperature of said oil to be regulated by automatic water cooled treatment.

Other features and advantages will be reflected from the accompanying pictorial drawings and the description and concluding claim.

In the drawings:

Figure 1 may be described either as a top or face view of the improved oil cooler with parts appearing in elevation.

Figure 2 is an end view of Figure 1.

Figure 3 is a horizontal sectional view taken on the central plane of the device.

Figure 4 is a side or edge view.

Referring now to the drawings by distinguishing numerals, it will be observed that the device, as a unit, is formed from a single metal casting, it is preferably bronze or some suitable non-corrosive metal. The manifold or casing proper is denoted by the numeral 5 and may be described as of general rectangular configuration in plan view with its longitudinal ends slightly rounded or of convex form. This shape is calculated to facilitate free flow of the oil as is obvious. On the exterior of the manifold I provide spaced par-

allel radiation fins 6. These contribute to the ultimate success of the device in effectively cooling the oil, as is obvious. The ends of the manifold are formed with a plurality of threaded openings to accommodate removable plugs. These may be separately distinguished for purposes of convenience. That is to say the openings or ports 7 (see Figure 3) may be described as the oil inlet and the one 8 diagonally in the opposite corner is denoted as the outlet. Suitable oil circulating pipes (not shown) are obviously attached to these nipples. The plugged opening 9 may be known as a priming hole while the similar plugged one in the bottom indicated at 10 may constitute a convenient drain. Incidentally, in practice, 15 the device may well be placed in a substantially vertical position but this is of course, not necessary.

The integrated oil conduit is located on the interior of the manifold and includes an annulus 11 which may be described as a coil and this in effect defines a circulation hole 12 through which the oil passes in a somewhat tortuous manner. The diametrically opposed coil connections 13 and 14 are in alignment with the attaching necks 15 and 16 respectively which extend to the exterior for connection with a water conducting pipe. It is obvious that by circulating water through the coil and at the same time passing oil through the manifold in and around the coil, the oil is sufficiently cooled to substantially regulate the temperature for engine conditioning. The circumference of the coil 11 is preferably such that it serves as a baffle and obstruction so as to prevent the oil from flowing straight through without being subjected to the cooling action of the water. Likewise, the cross sectional dimension or diameter of the coil is approximately one half of that of the transverse dimension of the manifold. Therefore, the coil may be centrally located so that its top and bottom or opposite faces are disposed in parallelism to the corresponding walls of the manifold. By properly proportioning the parts efficiency in circulation and cooling is assured.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details coming within the field of invention claimed may be resorted to in actual practice, if desired.

Having thus described the invention, what is claimed as new is:

A one-piece casting comprising a substantially rectangular casing having external fins provided at one end with an oil inlet and at a diagonally opposite end with an oil outlet, said casing being further provided with priming means and drain

means, an annular coil located centrally in the casing and having diametrically opposed connections with the end walls of the casing, said connections extending to the exterior to facilitate connection of a water supply pipe thereto.

JAMES FLOCKHART.
